COMPOSITION AND METHOD FOR DETERMINA-
TION OF ALBUMIN IN FLUIDS, PARTICULARLY
URINE

3 Claims. (Cl. 23—230)

This invention relates to a composition and to a method of using that composition for the determination of albumin in body fluids such as urine, for example.

Inasmuch as the presence of albumin in urine is an indication of a diseased or traumatic condition, the utility of a simple test for the determination of albumin is obvious. The methods of present day use for the determination of albumin in urine consist of the following qualitative tests:

(a) Heat test with acetic acid which involves boiling a measured quantity of urine and then adding equal amounts of acetic acid—a turbidity is formed in a positive specimen.

(b) Heller's test which involves placing an amount of concentrated nitric acid in a test tube and stratifying a small amount of urine on the nitric acid. A cloudy ring at the junction of the two liquids indicates a positive specimen.

(c) Sulfosalicylic acid test which requires the placing of 4 or 5 ml. of urine in a test tube and adding two or three drops of an aqueous solution of sulfosalicylic acid and a turbidity indicating a positive specimen.

(d) Picric acid test which involves placing a measured amount of urine in a test tube and adding an equal amount of saturated picric acid solution. Turbidity of the solution indicates a positive specimen.

The foregoing, and modifications thereof, constitute the presently employed methods of determination of the presence of albumin in urine, all of which depend on a turbidity test. In these, as indicated above, the albumin is precipitated either as a ring at the junction of the specimen and the precipitating agent, or as a suspension where the specimen is thoroughly mixed with the precipitating reagent.

Now, in order to circumvent the difficulties inherently involved in turbidity testing, to eliminate the preparation of solutions, and to avoid handling of corrosive acids, we have developed a composition and method for albumin determinations that is unique in its ease of application. The nature of the composition and method of use is such that an unskilled person can conduct the test and can, moreover, readily run mass screening test determination on large groups of urine specimens. These and related advantages are achieved by the present invention by means of a color test, a color test which is purely of the changing color variety rather than of the turbidity type.

In particular, the objects and advantages sought are obtained by the use of a tabletted composition which indicates concentrations of albumin in urine when only one or two drops of the specimen to be tested is placed upon the tablet. The composition of that tablet in general includes a protein precipitant comprising a member of one or more of the following groups: (1) a strong, solid, water-soluble acid such as sulfosalicylic acid or picric acid, (2) the alkali metal phosphates as are particularly represented by sodium tetrametaphosphate or sodium hexametaphosphate, and (3) metal salts such as lead nitrate, zinc sulfate, barium chloride, aluminum sulfate or aluminum chloride. A second ingredient of the present composition comprises, an effervescent couple consisting of a strong, solid, water-soluble acid such as those listed above as protein precipitants or maleic, tartaric,

2

citric, itaconic, sulfamic and like acids, together with an alkali metal carbonate or bicarbonate, the effervescent couple being effective to produce carbon dioxide in an aqueous medium. The third primary ingredient is a dye component consisting of one or a plurality of dyes at least one of which has an affinity for the protein as precipitated from solution to the extent that it is adsorbed upon the precipitated protein. In addition to its affinity for the protein being precipitated, one or more of the dyes constituting the dye component must exhibit a color change from its acid to its basic color within the range of pH increase which the precipitated albumin uniquely exhibits.

Additional description of the concepts and conditions for practicing the invention will follow the ensuing detailed description of representative formulae in parts by weight of the compositions contemplated by this invention.

Examples

	I	II	III	IV
Sulfamic Acid	15	15	15	15
Sulfosalicylic Acid	7	7	7	7
Sodium Tetrametaphosphate	6	6	6	6
Sodium Bicarbonate	8	8	8	8
Calcium Sulfate	3	3	3	3
External D & C Yellow #1*	.015			
Crystal Violet		.015		
Basic Fuchsine			.020	
Brilliant Green				.020

* Monosodium salt of 4-m-sulphenylazo-diphenylamine.

	V	VI	VII	VIII
Citric acid, anhyd	15	15	15	
Sulfosalicylic acid, anhyd	7	7	7	
Calcium sulfate	3	3	3	3
Boric acid	2.4	2.4	2.4	2.4
Sodium bicarbonate	.8	.8	.8	.8
Sodium tetrametaphosphate				
Sulfamic acid			6	6
Brilliant Green	.03	.03		15
F D C Violet #1		.03		
P-(p-Anilinophenylazo) benzene sulfonic acid sodium salt			.025	
Crystal Violet				.015

Possibly the preferred formula, but which at the same time is subject to variations, is the following in conjunction with which we have indicated the degrees of variation permissible in the several ingredients even to the point of eliminating certain of the constituents entirely:

Example IX

	Variation
Citric acid	17 0-20
Sulfosalicylic acid	6.8 5-40
Calcium sulfate	3 0-8
Tartrazine	.005 0-.010
Brilliant Green	.015 .010-.020
Sodium bicarbonate	.8 .0-1.0
Boric acid	2.4 0-8
Sodium hexametaphosphate	6 2-10

In all of the foregoing examples, precipitation of the protein was effected below its iso-electric point. In particular, sulfosalicylic acid, picric acid, sodium tetrametaphosphate and sodium hexametaphosphate are examples of chemicals which will precipitate protein below the iso-electric point, the sodium tetrametaphosphate and hexametaphosphate requiring additional acidity such as is provided by sulfamic or citric acids, for example. When precipitating the albumin below its iso-electric point, the reactant mixture should be at a pH no higher than 3 and consequently the dye component must change from the acidic color to the basic color at or below a pH of 3. In practice, the optimum pH for the precipitation appears to be in the range of 2.0 to 2.5.

As indicated in the earlier general discussion, not all dyes changing color below a pH of 3 can be used in the dye component. At least one of the dyes, where more than one dye is employed, must have an affinity for protein and must also have sufficient tinctorial strength to make color changes sufficiently definite for easy, accurate readings. Dyes which possess these desirable or essential attributes are Brilliant Green (sulfate salt of tetraethylidiaminotriphenylmethane), Crystal Violet (hexamethylpararosaniline chloride), Cresol Red (o-cresolsulfonphthalein), p-(p-anilinophenylazo) benzene sulfonic acid-sodium salt, Malachite Green (zinc double oxalate of tetramethyl-p-aminotriphenyl-carbinol, m-(p-anilinophenylazo) benzene sulfonic acid-sodium salt, Brilliant Blue (disodium salt of 4-[(4-N-ethyl-p-sulfobenzylamino) - phenyl] - (2 - sulfonumphenyl) - methylene)-[1-(N - ethyl - N - p - sulfobenzyl) - 2¹⁵ - cyclohexadienimine], FD & C Violet #1, and Tartrazine (trisodium salt of 3-carboxy-5-hydroxy-1-p-sulfophenyl-4-p-sulfophenylazopyrazole). Metanil Yellow (monosodium salt of 4-m-sulfophenylazodiphenylamine) and Basic Fuchsin (a mixture of rosaniline and pararosaniline hydrochlorides) are examples of dyes that are suitably adsorbed upon the precipitated protein but which give a more difficultly determinable result because of their weak tinctorial effect.

In Example IX, the sulfosalicylic acid and the sodium hexametaphosphate, both separately and together, precipitate the protein, the acid providing sufficient acidity for the hexametaphosphate to function. As an economical measure, the cheaper citric acid is included to provide additional acidity both for the pH regulation necessary for protein precipitation by the hexametaphosphate and for reaction with the sodium bicarbonate to produce effervescence. In this particular formula, Tartrazine is included only to modify the background color of the tablet whereas Brilliant Green provides the color change for the reading of the test. Calcium sulfate is used as a filler and boric acid as a lubricant to aid tabletting.

For precipitating albumin above its iso-electric point, we have found that lead nitrate, zinc sulfate, barium chloride, aluminum sulfate and aluminum chloride exemplify the water-soluble salts of metals that will function in this role. Specific formulae which are representative of other operable compositions include the following in parts by weight:

Examples

	X	XI	XII	XIII
Citric acid	3	3	3	5
Sodium acetate	16		16	14
Methyl red (p-dimethylamino-azo-benzene-o-carboxylic acid)	.015		.015	.8
Sodium bicarbonate	.8	.8	.8	.8
Boric acid	3	3	3	3
Lead nitrate	6			.015
Bromoresol Green		.015		
Zinc sulfate		6		6
Barium chloride				
Aluminum sulfate			16	
Sodium citrate				

	XIV	XV	XVI	XVII
Citric acid	5	3	3	3
Sodium bicarbonate	.8	.8	.8	.8
Sodium citrate	14	10	10	9
Aluminum sulfate	6	6	6	6
Boric acid	3	3	3	11
Sodium borate		6	7	
4-(4-dimethylamino-1-naphthazo)-3-methoxy-benzen sulfonic acid	.02			
Resazurin-Diazoresorcinol		.015		
Lacmoid $C_6H_2(OH)_3-N-(C_6H_3(OH)_2)_2$			.015	
Propyl Red (anthranilic acid di-n-propyl aniline)				.015

The foregoing are illustrative examples using Bromoresol Green (tetrabromo-m-cresolsulfon-phthalein), Resazurin ("Diazoresorcinol"), Lacmoid (heptahydroxy-

triphenylamine) and Propyl Red (anthranilic acid-di-n-propyl aniline) separately as the indicator dye although here again it is a contemplated possibility that any of these representative dyes may be used in combination with other dyes to form a dye component. In general, a dye which changes color above a pH of 6 will not give a color difference inasmuch as a pH of 6 seems to be the highest pH at which the method and composition will work when the protein is precipitated above its iso-electric point.

To again illustrate the variations that are possible in formulae where precipitation of the protein occurs above the iso-electric point, we have selected a preferred formula and have included possible variations of each ingredient in parts by weight, as follows:

Example XVIII

	Variation
Citric acid	5
Bromoresol Green	.02
Aluminum sulfate	6
Sodium bicarbonate	3
Sodium citrate	14
	3-7
	.01-.05
	4-10
	2-5
	11-18

It can thus be seen that the precipitation of albumin can be accomplished either below or above its iso-electric point with no resulting difference in the protein's property of increasing its pH to a point higher than that of the liquid and tablet. In either case, the practice of the invention is the same; one or two drops of the urine specimen are placed on the tablet. Functionally speaking, the sodium bicarbonate which with the acids present forms an effervescent couple, provides a means for the release of the active ingredients of the tablets and also provides a controlled mechanical means for the isolation of the precipitated protein which will possess a distinctive color in the case of a positive specimen. Through effervescence at the tablet surface, the precipitated protein is concentrated and isolated on top of the liquid. Apparently, at the moment of its precipitation, the albumin entraps sufficient carbon dioxide to cause the albumin to rise to the surface and remain there. Conversely, in the case of a negative specimen, foaming subsides more quickly, and within a few seconds specifically, the liquid remaining on the tablet being free of bubbles and being, of course, of the same color as the original solution. The latter effect as it applies to the liquid itself is always the case in both negative and positive specimens. For example, in the case of the formula containing Brilliant Green as the dye component, the foam which rises from the tablet surface will become blue, the amount and intensity depending on the quantity of albumin present. The tablet and liquid underneath the foam will remain an orange-yellow and the foam, if present, will also be orange-yellow in a negative specimen. With Crystal Violet, the color change is from the original purple to a green positive; for Basic Fuchsin the color change is from pale yellow to a light red; and for External D & C Yellow No. 1 the color changes from violet to yellow. For any dye that is selected, the change will be from its acid color to its basic color in positive specimens within the capacity and range of pH increase effected by the precipitated protein as has been earlier discussed.

Although we have described our invention in relation to urinalysis, it is evident from the broad principles taught that modifications can be readily made where necessary to extend the area of application of the method and composition to other body fluids. Within the area of this and other obvious modifications of the invention we claim:

1. A method for the determination of albumin in a liquid which comprises depositing a test portion of the liquid on a tableted mixture of a protein precipitant, a dye having an affinity for the precipitated protein and

which exhibits a color-change within the variation of pH effected by the precipitated protein, and an effervescent couple effective when moistened by said liquid to release carbon dioxide, said carbon dioxide forming with said liquid a foam on the surface of said tablet, said foam including the dyed albumin precipitated from said liquid.

2. In a method for determining albumin in a liquid, the step which comprises precipitating albumin from said liquid by depositing a test portion of the liquid on a tablet comprising a mixture of a protein precipitant, a dye having an affinity for the precipitated protein and which exhibits a color change within the variation of pH effected by the precipitated protein, and an effervescent couple effective when moistened by said liquid to release carbon dioxide, whereby said carbon dioxide forms a foam with said liquid on the surface of said tablet, said foam including dyed precipitated albumin.

3. A composition for determining the presence of albumin in liquids, comprising a tableted mixture of a protein precipitant selected from the group of metal salts consisting of lead nitrate, zinc sulfate, barium chloride, aluminum sulfate and aluminum chloride, a dye having an affinity for the precipitated protein, said dye exhibiting a color change within the range of pH increase

effected by such precipitated protein, and an effervescent couple consisting essentially of a strong water-soluble organic acid and a member of the group consisting of alkali metal carbonates and bicarbonates.
